[57] CLAIM

The ornamental design for a ski equipment carrier, as shown and described.

DESCRIPTION

FIG. 1 is a top, front, and right side perspective view of a ski carrier showing my new design;

FIG. 2 is a top plan view thereof;

FIG. 3 is a bottom plan view thereof;

FIG. 4 is a front elevational view thereof;

FIG. 5 is a right side elevational view thereof;

FIG. 6 is a left side elevational view thereof;

FIG. 7 is a rear elevational view thereof;

FIG. 8 is an enlarged top, rear, and right side perspective view thereof, showing the carrier employed to hold ski equipment, with the broken-line disclosure of the ski equipment being for illustrative purposes only and forming no part of the claimed design; and,

FIG. 9 is an enlarged top, rear, and left side perspective view thereof, showing the carrier fully folded up for storage.

The vertical strap is shown broken-away in the views for convenience of illustration.
